CARRYING HANDLE FOR FOOD CONTAINERS OR THE LIKE

James B. Swett, Barrington, R.I., assignor to Rexall Drug
and Chemical Company, Los Angeles, Calif., a corpo-
ration of Delaware

Filed Oct. 6, 1965, Ser. No. 87,348

Term of patent 14 years

(Cl. D44—29)

FIG. 1

FIG. 2

FIG. 3

FIG. 4

FIGURE 1 is a perspective view of a carrying handle for food containers or the like showing my new design, with a food container shown in broken lines for illustrative purposes only;

FIGURE 2 is a top plan view thereof;

FIGURE 3 is a side view thereof; and,

FIGURE 4 is an end view thereof.

The characteristic feature of my design resides in the slightly widened solid material central portion of the handle.

I claim:

The ornamental design for a carrying handle for food containers or the like, substantially as shown and described.
